MEANS FOR DETERMINING DRILLING
FLUID CHARACTERISTICS

William H. Collins, Houston, Tex.

Application February 19, 1937, Serial No. 126,592

1 Claim. (Cl. 73—51)

The invention relates to a means for determining the various characteristics of well drilling fluid, such as the weight per gallon, the viscosity thereof, the tendency to gel, and the sand content.

In the drilling of oil wells by the rotary method it is the practice to circulate a drilling fluid downwardly through the drill stem as it rotates, outwardly through the drill bit, and upwardly through the well bore outside of the drill stem to the surface. This circulation of drilling fluid serves many purposes, such as the carrying away of the cuttings from the drill bit, the cooling of the drill bit, the maintaining of a pressure against the wall of the formation so as to prevent caving and to prevent the inrush of foreign substances from the formation, as well as to overcome gas pressures which are encountered by the drill bit.

It is obvious, therefore, that the characteristics of the drilling fluid must be accurately known and controlled at all times in order that all of its varied functions may be properly performed. The weight must be accurately controlled in order that the desired pressure will be exerted on the formation to prevent blowing out of the well. The viscosity of the fluid must be accurately controlled so as to obtain proper circulation without excessive friction losses and to insure that the mud will not become filled with gas or gas cut, that is carrying an excessive amount of gas in suspension. The gelling qualities of the mud must also be known because in some instances the drilling operation is shut down and if there is too great a tendency of the mud to gel, then, of course, it would stick the drill pipe and prevent further operation in the well and, lastly, it is desirable to know the sand content of the mud so that the size of the slush pit can be varied or the volume of mud used for the drilling operation controlled, so as to permit the sand to settle out of the mud or to remove it by proper chemical or mechanical means.

It is one of the objects of the invention to provide an apparatus which can be readily utilized to ascertain all four of the foregoing characteristics in a minimum of time on the derrick floor.

Another object of the invention is to provide a hydrometer and viscosimeter for use with drilling fluid.

Still another object of the invention is to provide a container having graduations thereon to indicate the amount of immersion of the container in a liquid and a window therein to ascertain the level of the contents in the container.

Other and further objects of the invention will be readily apparent when the following description is considered in connection with the accompanying drawing wherein:

Fig. 1 is a vertical sectional view showing the arrangement and relative position of the parts when the weight per gallon of a sample of the drilling fluid is being determined.

Fig. 2 is a vertical sectional view showing one manner of obtaining the gelling qualities of a sample of the drilling fluid.

Fig. 3 shows a modified form of container whereby the level of the fluid therein can be accurately determined.

Fig. 4 is a section taken on the line 4—4 of 15 Fig. 3.

In Fig. 1 a receptacle 2 has been generally illustrated which contains a body of water 3. This body of water is of sufficient depth to float the container 4 when it contains a predetermined body of drilling fluid 5. As seen in the drawing, the drilling fluid has a greater specific gravity than that of water because the volume of water displaced is greater than the volume of the drilling fluid, and the amount of immersion of the container or tube 4 can be readily ascertained by observing the graduations 7 on the side thereof as an indication of the specific gravity or weight per gallon of the sample of drilling fluid.

A predetermined volume of drilling fluid 5 has been placed in the container 4 and this volume is indicated by the graduations 9 on a window 10 in the side of the tube. In this manner the volume can be accurately determined and, as seen in Fig. 1, there are other graduation lines on the window, such as 11 and 12. As an illustration, the line 12 may indicate 500 cubic centimeters. The line 11 may indicate 1000, and the line 9 indicate 1500. Any other units of measurement may, of course, be used.

The graduations 7 may be calibrated in any desired manner but the practice in the drilling industry is to indicate the specific gravity of the drilling fluid by the pounds per gallon and it is the usual practice to use drilling muds which vary from 9 to 12 pounds per gallon. In some instances muds having greater or lesser weights are also used. Of course, the weight of water is well known to be 8.3 pounds per gallon.

The container 4 is provided at its base with an orifice 15 which may be in the form of a stop cock 16. This stop cock may be open or closed as desired in order to permit a flow of fluid from the container. This container may be made of

any suitable material, either opaque or transparent.

The viscosity of the mud 5 in the container can be readily determined by observing the 5 period of time which is required for a given quantity such as 500 or 1000 c. c. of fluid to flow through the orifice 15. Any size orifice may be provided and by suitable computation the viscosity can be determined.

10 This container of Fig. 1 is of particular advantage because if the weight per gallon and the viscosity are to be determined it is only necessary to dispose a predetermined volume of drilling fluid in the container, immerse it in the 15 water in the receptacle 2, so as to read the weight per gallon directly from the graduation 7. The container is then removed and the stop cock 16 opened so that the time may be observed which is required for this body of drilling fluid to escape 20 from the container. Thus in a very short period of time and with very little difficulty the weight and viscosity of the fluid can be determined very accurately so that readings can be taken very frequently as the drilling fluid discharges or 25 enters the well.

In Fig. 2 one manner of ascertaining the gelling tendency of the drilling fluid is shown. In this arrangement the receptacle 2 contains a body 20 of drilling fluid which is, of course, similar to the 30 drilling fluid at 5. In this form the container 4 has a body of water 21 disposed therein of a predetermined volume, as indicated by the level line 22 on the window 23.

A number of graduations 24 are shown on the 35 periphery of the tube or container 4 which may be used to indicate the extent of the immersion of the tube in the drilling fluid 20. Inasmuch as the weight per gallon of the drilling fluid 20 is known, then of course a predetermined volume 40 of water, as at 21, should displace a predetermined volume of the drilling fluid. If, however, the drilling fluid has a tendency to gel there will be an increase in the frictional resistance around the outside of the tube due to this tendency, and 45 the tube will not sink into the drilling fluid the proper amount. This tendency to gel is determined over different periods of time. A sample of the drilling fluid may be taken from the return line and placed in the receptacle 2 and the container 4 immediately placed therein. The 50 amount of "initial gel" is thus determined. The container is then removed and after a period of five minutes the tube may be again inserted and again observed, and this will be known as the 55 five-minute gel. These indications may be carried on for ten or fifteen minutes or other periods of time as desired so that the tendency to gel and to cause difficulty in the well bore can be readily observed.

60 In order to obtain an accurate test of the viscosity various volumes of the drilling fluid may be placed in the container 4. For instance, the first test may consist of depositing 1500 cc. in the container and observing the time necessary 65 to withdraw 1000 cc. thereof. The next test may consist of depositing 1500 cc. in the container and withdrawing 500, while the third test may consist of putting in 500 and withdrawing 500. Thus, an average of the times for the volume considered may be taken and in this manner 70 a balance obtained for the various friction losses.

In order to determine the sand content of a

sample of the drilling fluid a predetermined volume may be placed in the container 4 and any desired amount of water added thereto. Agitation of the water and the drilling fluid results in its dilution so that the heavier particles 5 of sand will have a tendency to settle to the bottom. The liquid can be removed from the top and the operation repeated until only clear water remains in the tube with the sand settled at the base thereof, for the purpose of ascertaining 10 the percentage of sand as compared with the original volume of drilling fluid which was placed in the container. As an example, if 1,000 cc. of drilling fluid to the level of line 11 was originally placed in the tube and the graduations 15 25 show the level of the sand which remains, it is an obvious calculation to determine the percentage of sand which was present in the sample of drilling fluid.

A list of the colloidal properties of the drilling 20 mud may be made with the container 4 by depositing a given quantity of water therein and thoroughly mixing with it a small percentage of mud. When allowed to stand the amount of the mud which settles out of the water is an 25 indication of the colloidal properties. The graduations may be used to indicate the percentages.

Another form of ascertaining the gel qualities 30 of the mud would be to dispose samples of the mud both in the receptacle 2 and the container 4; then 35 when the receptacle is placed in the mud in the container 2 the resistance to settling could be determined by observing the graduations 24 and any arbitrary unit of measurement utilized to determine the gel quality, such as percentage of 35 an inch or relative percentage of settling of the sample with respect to the mud in the container.

A modified form of the container 4 is illustrated 40 in Fig. 3 where the container is composed of a lower portion 30 and an upper portion 31. These two parts are interconnected by the joint 32 and the upper portion 31 having an opening 33 therein and the lower portion 30 having an opening 34. Normally these openings are out of alignment, as seen in Fig. 4, but by relative rotation 45 of the parts they may be moved into alignment. Thus any liquid in the container would flow out the opening 34 down to the level of the bottom of the openings as at 35 in Fig. 3. In this manner if the container were solid metal or other 50 opaque material the level could be accurately determined without the provision of the windows, such as 10 or 23 shown in Figs. 1 and 2, respectively. It is to be understood that the container of Figs. 1 and 2 may be the same container with 55 the graduations and windows on opposite sides thereof if desired.

Broadly the invention contemplates a simple 60 and economical means for determining the four characteristics of a drilling fluid which are essential to its proper use.

What is claimed as new is:

In a combination viscosimeter, hydrometer, and gel testing device, comprising an open topped container of uniform diameter throughout its length, a valve controlled viscosity tube mounted centrally in the base thereof through which the fluid will pass by gravity, indicia on said container to indicate its contents or its degree of immersion for determining specific 65 gravity and gelling characteristics.
